US0D1067904S

(12) **United States Design Patent** (10) **Patent No.:** **US D1,067,904 S**
(45) **Date of Patent:** **** Mar. 25, 2025**

(54) **CASE FOR ELECTRONIC DEVICE**

(71) Applicant: **Samsung Electronics Co., Ltd.**, Suwon-si (KR)

(72) Inventors: **Ki-Eon Lee**, Suwon-si (KR); **Saewon Kwon**, Suwon-si (KR); **Seungbin Im**, Suwon-si (KR); **Keemoon Lee**, Suwon-si (KR); **Kisung Kim**, Suwon-si (KR); **Sangsik Park**, Suwon-si (KR)

(73) Assignee: **SAMSUNG ELECTRONICS CO., LTD.**, Gyeonggi-Do (KR)

(**) Term: **15 Years**

(21) Appl. No.: **29/889,534**

(22) Filed: **Apr. 13, 2023**

(30) **Foreign Application Priority Data**

Mar. 9, 2023 (KR) 30-2023-0008956

(57) **CLAIM**

The ornamental design for a case for electronic device, as shown and described.

DESCRIPTION

FIG. 1 is a front perspective view of a case for electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is an exploded view thereof;

FIG. 10 is another exploded view thereof;

FIG. 11 is an enlarged view of the delineated portion 11 in FIG. 1;

FIG. 12 is an enlarged view of the delineated portion 12 in FIG. 3; and,

FIG. 13 is an enlarged view of the delineated portion 13 in FIG. 4.

The even-dash broken lines illustrating portions of the case for electronic device form no part of the claimed design. The dot-dash broken lines encircling enlargement portions of the design form no part of the claimed design. The bracket in FIGS. 9 and 10 to show the relationship or order of assembly of various parts of the case for electronic device form no part of the claimed design.

1 Claim, 13 Drawing Sheets
